ATTORNEY

UNITED STATES PATENT OFFICE

131,892

DESIGN FOR A TRACTOR CAB

Harold W. Bostrom, Milwaukee, Wis.

Application April 29, 1940, Serial No. 92,027

Term of patent 14 years

To all whom it may concern:

Be it known that I, Harold W. Bostrom, a citizen of the United States, residing at 133 East Washington Street, in the county of Milwaukee and State of Wisconsin, have invented a new, original, and ornamental Design for Tractor Cabs, of which the following is a specification, reference being had to the accompanying drawing, forming part thereof.

Fig. 1 is a front perspective view of a tractor cab, showing my new design;

Fig. 2 is a rear perspective view of the cab; and

Fig. 3 is a side elevational view thereof.

I claim:

The ornamental design for a tractor cab, as shown.

HAROLD W. BOSTROM.
